ATTORNEY.

UNITED STATES PATENT OFFICE.

JAMES ROBERT McELRATH, OF NESCOPECK, PENNSYLVANIA, ASSIGNOR OF ONE-THIRD TO W. J. WALKER AND ONE-THIRD TO CHARLES W. ROBLES, BOTH OF NEWARK, NEW JERSEY.

VALVE.

Application filed October 26, 1920. Serial No. 419,600.

To all whom it may concern:

Be it known that I, JAMES ROBERT McELRATH, a citizen of the United States, residing at Nescopeck, in the county of 5 Luzerne and State of Pennsylvania, have invented certain new and useful Improvements in a Valve, of which the following is a specification.

This invention relates to a valve mechanism designed for use in connection with 10 hydraulic presses and has for its object to provide, in a manner as hereinafter set forth, means whereby the exhaust water from the main cylinder of the press is quickly returned to the reservoir therefor simultaneously with the raising of the ram of the 15 press.

With reference to the operation of hydraulic presses, the cylinder thereof is supplied with reservoir or low pressure water 20 during the down stroke of the ram or plunger to overcome the employment of too much high pressure water, and immediately the material, which is to be operated on, is impacted upon by the ram or plunger, the valve controlling the supply of low pressure is closed and this closing of the valve divides the high pressure from the low pressure supply. The operation of the ram or plunger on 25 the material is had by high pressure water. In the general form of hydraulic presses, the supply valve mechanism employed in connection therewith, is such that it will not permit the low pressure water to pass directly therethrough to the reservoir from the cylinder on release of the ram, and such low pressure water will have to pass back through the high pressure supply, thence through the operating valve at the base of 30 the press and then be returned to the top of the reservoir, traveling a distance of about sixty feet in all, under such operation the press is a very slow acting one caused by the time of return of the water and also 35 through the friction set up by the short bends and short pipes through which the water travels to the reservoir, and to overcome this direction of travel of the water on its return to the reservoir, as well as to provide for a 40 quick return and a quick acting press, is the primary object of this invention, and this is accomplished, in a manner as herein-after set forth, by the providing of means

to open the valvular element, of the supply valve mechanism associated with the supply 55 of the low pressure water from the reservoir, immediately upon the starting of the release of the press whereby the low pressure water can return directly through the supply valve mechanism to the reservoir, and 60 such return requiring but a travel of approximately four feet, and such short travel of the low pressure water to the reservoir will, as is obvious, materially quicken or increase speed 65 of the press.

Further objects of the invention are to provide a valve mechanism for the purpose set forth which is simple in its construction and arrangement, strong, durable, efficient in its use, readily set up and comparatively 70 inexpensive.

With the foregoing and other objects in view, the invention consists of the novel construction, combination and arrangement of parts, as hereinafter more specifically described and illustrated in the accompanying drawing, wherein is shown an embodiment of the invention, but it is to be understood that changes, variations and modifications can be resorted to which come within the 75 scope of the claims hereunto appended.

As illustrating, a valve mechanism in accordance with this invention for the purpose set forth, reference is had to the accompanying drawing which shows the valve mechanism in vertical section.

Referring to the drawing in detail, 1 denotes a valve casing provided with a combined inlet and exhaust channel 2, for low pressure water and which is adapted to communicate with a reservoir, not shown. The casing 1, is furthermore provided with a combined supply and exhaust port 8, which is adapted to open into the cylinder, not shown, of the press and extending from the 90 upper end of the port 8, is a port 9, which opens into a high pressure water pipe, not shown. The valve casing 1, is also provided with a water space 6, and a port 7, leading from the latter and opening into the ports 8, 95 9. A vertical passage 3^a, arranged centrally of the casing 1, is provided for establishing communication between the water space 6, and the inner end of the channel 2, and at the upper end of the passage 3^a, an annular 100 valve seat 3, is mounted. At the upper por-

tion of the valve casing 1, it is formed with a vertically disposed opening which communicates with the water space 6, and the said opening has a stepped wall 6^a, which 5 provides a shoulder 6^b, having a packing 6^c mounted thereon. That portion of the wall 6^a, above the shoulder 6^b, is threaded.

Engaging with the threaded portion of the wall 6^a, is a peripherally threaded plug 10 4^a, formed with a depending integral valve cage 4, which extends through the water space 6, and is mounted on the valve seat 3. The plug 4^a, is provided with a pair of oppositely extending pockets 4^b, 4^c, the former 15 being of greater diameter than the latter and arranged at the inner end of the plug 4^a. Positioned centrally of the pocket 4^b, is a depending abutment 5^a, formed with a central bore 5^b, which opens into the pocket 20 4^c, the latter has the wall thereof threaded.

Guided by and operating within the cage 4, as well as having its upward movement arrested by the abutment 5^a, is a cup shaped valve 5, which is adapted to engage the valve 25 seat 3, for the purpose of closing the water space 6, to the channel 2. The valve 5, is formed with a stem 10, which operates through the bore 5^b, and extends into and projects above the bottom of the pocket 4^c. Surrounding the stem 10, within the pocket 30 4^c, is a pair of oppositely disposed flanged leather packing rings 19, 19^a, which have interposed therebetween a bronze separator ring 20. The rings 19, 19^a, are similar in 35 construction and the flange of the ring 19^a is seated in a groove formed in the plug at the bottom of the pocket 4^c.

Threadably engaging with the wall of the 40 pocket 4^c, is a cylinder 12, which projects outwardly from the plug 4^a, and into which extends the stem 10. A bronze ring 18, encircles the stem 10 and is seated in the inner end of the cylinder 12. The flange of the packing ring 19, projects into the 45 ring 18.

The stem 10, has the upper terminal portion thereof threaded and has secured thereto a piston consisting of a shouldered collar 11, a packing element 15, and a cup shaped head 14. The packing element 15, is interposed between the collar 11, and the head 14, the latter has threaded engagement with the threaded terminal portion of the stem 10, and abuts against and compresses the element 15, against the collar 11. The head 14, is secured to the stem 10, by a transversely extending pin 10^a. The upper end of the cylinder 12, is formed with a vent opening 13.

60 The body of the cylinder 12, is formed with a lengthwise extending passage or conduit 16, which opens into the lower portion of the cylinder below the piston. The outer end of the passage 16, is threaded as 65 at 17, for the connection thereto of a high

pressure pipe, not shown, leading to the controlling valve, and the conduit 16, is provided for the purpose of admitting pressure to the cylinder 12, simultaneously when the pressure is supplied to lift the ram or plunger 70 whereby the piston in the cylinder 12, will be elevated, carrying the valve 5 therewith and establishing communication between the water space 6, and the channel 2, so that the low pressure water can be immediately 75 returned to the reservoir through the casting 1.

When the pressure is on in the main cylinder of the press in connection with which this valve is used, the valve 5 is closed and 80 when pressure is on in the main ram raising cylinder it is also on in passage 16 and operates to lift the piston 11 and through stem 10 opens valve 5, to permit the exhaust water to pass back through channel 2. The 85 leather flanged packing 19, 19^a, prevents the pressure from escaping to valve 5 and when pressure is on valve 5 the packing 19, 19^a produces a fluid tight joint between the two valves.

90 In the use of the valve 5 which is normally closed and which is used in connection with a hydraulic press, the water to be supplied to the press cylinder enters through channel 2 and valve 5 and flows through port 8 to 95 the press cylinder (not shown). After the cylinder or cylinders have been filled the valve 5 automatically closes by gravity, cutting off water flowing from the reservoir, not shown, and the check valve 5 will be 100 held closed by the pressure in the press. When the pressure is released and the exhaust water is to be returned to the tank, pressure is admitted to the passage 16 from the controlling valve and operated to open 105 valve 5 for the return of the water from the press through channel 2. This turning on of the pressure in the pipe or passage 16, occurs the instant the pressure is released from the press cylinder and on the turning 110 on of the pressure to lift the ram of the press. This opening of the valve 5 allows the exhaust water to take a short cut through ports 8, 7 and 2 to the reservoir tank not 115 shown, which avoids the friction produced by the large volume of water returning through port 9, and the high pressure pipe, not shown, in the old way, which pipe is much smaller than channel 2, hence the passage of the water through channel 2 practically doubles the speed of the return stroke 120 of the main ram of the press.

125 The valve 5 by being equipped with the shifting mechanism as described is caused to operate positively as a check valve and a quick return valve thereby rendering the apparatus absolutely safe.

130 The preferred embodiment of the invention is disclosed in the drawing and set forth in the specification, but it will be understood

that any modifications within the scope of the claimed invention may be in the construction without departing from the principle of the invention or sacrificing any of its advantages.

What I claim is:—

1. A valve mechanism for use in connection with hydraulic presses comprising a casing formed with a port communicating 10 with a high pressure supply and with the cylinder of the press and further having a channel opening into a low pressure reservoir, a valvular element mounted in said casing for separating said port from said channel to discontinue low pressure supply to the press at the starting of the operation of the press on the material, and a high pressure operated means mounted in said casing and connected to said element for shifting it to open position to provide for the discharge of the water through the casing to the reservoir on the starting of the release of the press on the material.
2. A valve mechanism for use in connection with hydraulic presses comprising a casing formed with a port, communicating with the high pressure supply and with the cylinder of the press and further having a channel opening into a low pressure reservoir, a valvular element mounted in said casing for separating said port from said channel to discontinue low pressure supply to the press at the starting of the operation of the press on the material, a plug seated 35 in said casing and provided with a guide for said element, a cylinder secured in the plug and formed with a passage opening into the lower end thereof and communicating with the high pressure supply, a stem carried by said element and extending into said cylinder, a piston carried by the stem and arranged within said cylinder above the point of communication of the passage therewith for shifting said element to open 40 position on the supply of high pressure to the cylinder to provide for the discharge of water from the press through said channel to the reservoir simultaneously with the starting of the release of the press on the material, and an abutment carried by the plug for limiting the opening movement of said element.
3. A valve mechanism for use in connection with hydraulic presses comprising a casing formed with a port communicating with the high pressure supply and with the cylinder of the press and further having a channel opening into a low pressure reservoir, a valvular element mounted in said casing for separating said port from said channel to discontinue low pressure supply 55 to the press at the starting of the operation of the press on the material, a plug seated in said casing and provided with a guide for said element, a cylinder secured in the plug and formed with a passage opening into the lower end thereof and communicating with the high pressure supply, a stem carried by said element and extending into said cylinder, a piston carried by the stem and arranged within said cylinder above the point of communication of the passage therewith for shifting said element to open 60 position on the supply of high pressure to the press at the starting of the operation of the press on the material, a plug seated in said casing and provided with a guide for said element, a cylinder secured in the plug and formed with a passage opening into the lower end thereof and communicating with
4. A valve mechanism for use in connection with hydraulic presses comprising a casing formed with a port, communicating with the high pressure supply and with the cylinder of the press and further having a channel opening into a low pressure reservoir, a valvular element mounted in said casing for separating said port from said channel to discontinue low pressure supply 70 to the press at the starting of the operation of the press on the material, a plug seated in said casing and provided with a guide for said element, a cylinder secured in the plug and formed with a passage opening into the lower end thereof and communicating with the high pressure supply, a stem carried by said element and extending into said cylinder, a piston carried by the stem and arranged within said cylinder above the point of communication of the passage therewith for shifting said element to open 75 position on the supply of high pressure to the cylinder to provide for the discharge of water from the press through said channel to the reservoir simultaneously with the starting of the release of the press on the material, and packing elements interposed between the cylinder and plug and surrounding said stem.
5. A valve mechanism for use in connection with hydraulic presses comprising a casing formed with a port communicating with the high pressure supply and with the cylinder of the press and further having a channel opening into a low pressure reservoir, a valvular element mounted in said casing for separating said port from said channel to discontinue low pressure supply 80 to the press at the starting of the operation of the press on the material, a plug seated in said casing and provided with a guide for said element, a cylinder secured in the plug and formed with a passage opening into the lower end thereof and communicating with the high pressure supply, a stem carried by said element and extending into said cylinder, a piston carried by the stem and arranged within said cylinder above the point of communication of the passage therewith for shifting said element to open 85 position on the supply of high pressure to the cylinder to provide for the discharge of water from the press through said channel to the reservoir simultaneously with the starting of the release of the press on the material, and an abutment carried by the plug for limiting the opening movement of said element.

the cylinder to provide for the discharge of water from the press through said channel to the reservoir simultaneously with the starting of the release of the press on the 5 material, an abutment carried by the plug for limiting the opening movement of said

element, and packing elements interposed between said cylinder and plug and surrounding said stem.

In testimony whereof, I affix my signature hereto.

JAMES ROBERT McELRATH.
